MATCH BOOK

Charles C. Baldwin, St. Louis, Mo.

Application April 2, 1938, Serial No. 199,555

2 Claims. (Cl. 206—29)

This invention relates to match books or folders, and undertakes to provide as a new article of manufacture an improved form of match book, embodying certain unique features of construction and arrangement and also eliminating the usual method of lighting match splints, the said improvements relating more especially to match books embodying a match ignition chamber for facilitating the safe ignition of the match, and wherein the match splint cards or fillers are so shaped and attached at their base ends to the encompassing material of the folder or cover of the book as to co-operate in the formation of the said ignition chamber at that end of the book, the said chamber having one or more of its inner walls provided with a match ignition surface and being dimensioned for permitting the insertion of the match head, after which the withdrawal of the match under a slight pressure upon the walls of the chamber, will ensure its positive and safe lighting, the remaining flexible portions of the material of the cover or folder serving for providing a back and frontal flap or closure giving protection to the match heads and splints and assuring convenience and ease in the detachment of individual matches for use.

Another object is to provide a match book or folder having an ignition chamber or cavity which is entirely closed except at the laterally disposed ends of that portion of the book encompassing the base of the match card, the ignition material being incorporated upon one or more of the inner walls of the chamber, entirely protected from dirt or dampness, and in which chamber in the process of lighting a match, the head of the match splint is first inserted longitudinally and then withdrawn under a slight pressure upon the walls of the chamber, by which operation the match is lighted.

The accompanying drawing clearly illustrates certain preferred embodiments and features of the invention, the same being fully explained in the specification forming a part of this application, and being defined in the claims. In the drawing:

Figure 1 is a perspective view of a preferred form of the invention as applied to a match book, the cover flap being shown as open, and indicating the head of a match splint positioned for igniting, a portion of the encompassing end of the cover material being broken out for the purpose of showing part of the base portion of the match splint cards and the construction and arrangement of the ignition chamber.

Figure 2 is a closed position edge view of the

form shown in Figure 5, illustrating an end-on view of the ignition chamber in the base of the book.

Figure 3 is an interior plan view of the open cover or folder before complete assembly, with a double card of match splints constituting the filler laid thereupon, prior to its being folded for attachment, and the end of the cover with the ignition material indicated at either side of the narrow central portion of the card, which cover when folded upon and attached to the card will complete the ignition chamber.

Figure 4 is a plan view of a single card of match splints or fillers adaptable to another form of my invention.

Figure 5 is a perspective view of the second form of the folder already referred to, with the ignition chamber incorporated therein.

In practising my invention I provide fillers or inserts represented generally at 3 and 4 in the drawing, the same comprising cards of paper match splints, and which cards may be in the double form as shown in Fig. 3, and then folded over on the medial line 8, prior to assembly and attachment, or if preferred, single forms of the cards may be used and assembled together, the single cards, one form of which is shown in Fig. 4, being superimposed in exact alignment, to complete the filler, as shown in Fig. 2.

For the inserts or fillers thus formed, a flexible cover or folder 6 is provided, the same being of an oblong strip of any suitable material and being folded upon itself to form an encompassing integral end portion 9 with inwardly opposed faces, a back portion 10, folded at lines 7, a frontal closure flap 11. Ignition material 12 is applied upon one or more of the opposed, the inner faces of the integral end fold 9, the said material being extended laterally outward, clear to the outer edges of the cover, as clearly shown in the drawing. The fillers are positioned within the folders with their base marginal portions located and encompassed within the fold 9 where same are permanently secured by means of a wire staple or stitch 13 being passed through the assembly of match cards and overlying cover, and there clinched.

It will be noted that the filler 3 is formed with a centrally extended narrow portion 3a, and if this form is used in making up the books, then the base marginal edge of this narrow portion makes contact with the material of the cover forming the integral end fold 9. Thus with this form two separate ignition chambers 14 are formed and provided, one at either side of the

said narrow portion and in direct axial alignment with each other.

If however the form represented at 4 is used, then the face of the comparatively narrow base 5 marginal edge of the filler does not make contact with the said fold, but is positioned therefrom slightly, leaving a continuous tubular space extended through from side to side of the folder at this integral end thereof, which tubular space 10 constitutes an open ended ignition chamber 14 for this form of the assembly.

With whichever form of filler used, the folder is mounted thereon as stated, and the back portion 10 and frontal closure flap 11, operate in 15 conventional manner, the book being closed by simply inserting the extremity of the frontal flap down under the free edge of the opposed extremity of the end fold 9.

If preferred, the form of cover represented 20 in Figures 5 and 2 may be employed, wherein the front and back portions 10a, 11a of the folder are made of equal length and in parallel extension with the match splints for their full length and to a point just beyond the match 25 heads where the extreme free end of each is folded inwardly at a right angle so that the faces of said ends oppose each other in close proximity when the book is in closed position. This form of book may be readily manipulated with 30 one hand, the opening process is indicated in the drawing, the other hand being employed in detaching a match splint and igniting same in either end of the chamber 14.

It will be noted that the main feature of the 35 invention lies in the provision of the ignition chamber or chambers extended laterally in axial alignment out through the sides of the base end of the assembly, the said chambers being entirely inclosed by the integral and uncut material of the cover, and being formed between 40 the base portion of the match splints and the opposite or adjacent turns or folds of the cover material, there being suitable ignition material incorporated upon one or more of the inner walls

of the said chambers, these chambers being adapted as stated for engaging the head of the match splint, as and for the purpose described.

Obviously economies in manufacture are assured, and appearance enhanced, when the features embodied in the described forms of match books are present, besides making same more desirable as advertising mediums. And while I have herein shown and described certain structural features of the invention, it is understood 10 that I may vary same in minor details, not departing however from the spirit of the invention as defined in the appended claims.

I claim:

1. A match book comprising a flexible cover 15 member folded upon itself to provide a back portion, a frontal portion and an encompassing integral end portion, an assembly of match splint cards secured by their base ends within the encompassing integral end portion of the 20 cover, the said base ends at their outer lateral margins being spaced from the material of the cover to provide openings for the insertion of a match head, and ignition material located within the said openings and adapted to ignite the 25 match upon frictional contact therewith.

2. A match book comprising a card of matches having a base marginal portion so shaped as to provide a space longitudinally between its side marginal edges sufficient to permit the insertion 30 and withdrawal of the match head, a cover having an integral end folded upon and secured to the base marginal portion of the card, and having match igniting material upon one or more of the inner opposed faces of said integral end 35 fold, and co-operating with the match card in the formation of a match igniting chamber, which is entirely closed except at the laterally disposed ends of the encompassing integral end portion, and having a flexible portion providing a 40 back and a flap formation closure, said card and encompassing integral end of the cover being united by a staple or wire stitch.

CHARLES C. BALDWIN.
